UNITED STATES PATENT OFFICE.

JOHN F. O'CONNOR, OF CHICAGO, ILLINOIS, ASSIGNOR TO WILLIAM H. MINER, OF CHAZY, NEW YORK.

ROLLER SIDE BEARING.

1,179,748.

Specification of Letters Patent. Patented Apr. 18, 1916.

Application filed May 10, 1915. Serial No. 26,970.

To all whom it may concern:

Be it known that I, JOHN F. O'CONNOR, a citizen of the United States, residing at Chicago, in the county of Cook and State of Illinois, have invented a certain new and useful Improvement in Roller Side Bearings, of which the following is a full, clear, concise, and exact description, reference being had to the accompanying drawings, forming a part of this specification.

This invention relates to improvements in roller side bearings.

An object of the invention is to provide a roller side bearing for railway cars and the like which is of simple construction and wherein means are provided in the form of a bearing plate which also serves the function of protecting the anti-friction members from dirt and the weather.

The invention furthermore consists in the improvement in the parts and devices herein shown, described or claimed.

In the drawing forming a part of this specification, Figure 1 is an elevational view of portions of a body bolster and truck bolster of a car showing my improvements in connection therewith. Fig. 2 is an enlarged top plan view of the improved side bearing. Fig. 3 is a longitudinal vertical sectional view taken on the line 3-3 of Fig. 2, and Fig. 4 is a transverse vertical sectional view taken on the line 4-4 of Fig. 3.

In said drawing, 10 denotes the body bolster, 11 the truck bolster swiveled at their centers in the usual manner. The body bolster is provided with a bearing casting or plate 12 on its under side and, as shown, the improved roller bearing A is attached to the truck bolster.

The roller bearing A comprises a base casting 13 having end flanges 14, by which it is adapted to be riveted or otherwise secured to the bolster. The casting 13 is also provided with spaced side walls 15 and 16, the latter being curved along its upper edge as indicated at 17 to form a spring chamber for a longitudinally arranged spring 18. The bottom of the casting 13 is cut away as indicated at 19 in order to permit any foreign matter to fall therethrough, and also to lighten the casting. Mounted between the side walls 15 and 16 are anti-friction rollers 20-20, the same being supported by shafts

or journals 21-21 having their ends supported in the side walls, the ends of the journals 21 being beveled as indicated at 22 and adapted to be held in fixed position by peening or upsetting of the partitions or walls 23-23 in the side walls 15 and 16. Suitable bushings 24 are preferably interposed between each of the journals 21 and the corresponding rollers. In order to provide a more substantial bearing and to more uniformly distribute the load, I provide a bearing plate 25 of case hardened material which bearing plate 25, as shown, is substantially of inverted U-shape in cross section and has the sides 26 and 27 thereof extending downwardly over the ends of the anti-friction rollers between the latter and the side walls 15 and 16, each of the depending sides 26 and 27 of the bearing plate having an elongated slot 28 to accommodate the journals 21 and permit the bearing plate to slide back and forth. On the side adjacent the spring 18 the bearing plate 25 is provided near its ends with laterally extending lugs or projections 29-29 which act as followers and engage the ends of the spring 18. The ends of the spring 18 also engage shoulders 30-30, formed integrally with the curved section 17 at its ends and which thus act as stops for the spring.

In operation, when relative turning of the bolsters occurs and pressure is exerted from the thrust block 12 against the bearing plate 25 the latter will move in accordance with the direction of movement of the body bolster, and in being so moved, the plate 25 will roll upon the anti-friction rollers 20. This movement of the plate 25 will, of course, compress the spring 18 and upon release of the pressure on the plate 25 the latter will be immediately returned to normal central position under the influence of said spring. As will be understood, the travel of the plate 25 is limited in either direction by the same engaging at the ends of the slots 28 with the corresponding journal or shaft 21.

From the preceding description it will be seen that the device which I have devised consists of relatively few parts which may be readily assembled and disassembled and various elements replaced; the pressure is distributed over a large area; and the bearing plate 25 is so designed that it protects

the anti-friction rollers from the weather and acts as a shedder of rain, sleet, dirt, etc.

I claim:

1. In a roller side bearing, the combination with a base casting having spaced side walls and anti-friction rollers rotatably mounted between said walls on journals supported thereby, of a bearing plate mounted on said rollers and adapted to slide back and forth relatively to said casting, said plate being substantially U-shaped in cross section and extending over the ends of said rollers and slotted to receive said journals therethrough, and spring means for centering said plate.

2. In a roller side bearing the combination with a base casting having spaced, upstanding side walls, anti-friction rollers

mounted between said walls, fixed journals supported at their ends in said walls and 20 on which said rollers are rotatably mounted, of a bearing plate mounted on the top of said rollers and adapted to slide back and forth relatively to said casting, said casting being provided with a spring chamber 25 along one side thereof, a spring mounted within said chamber, and projections at the side of said bearing plate engaging the ends of said spring, said spring centering the plate after each actuation of the side bearing.

In witness that I claim the foregoing I have hereunto subscribed my name this 24th day of April 1915.

JOHN F. O'CONNOR.
